CLAIM

The ornamental design for a natural nipple, as shown and described.

DESCRIPTION

FIG. 1 is a perspective view of a natural nipple showing my new design;

FIG. 2 is a front elevational view thereof;

FIG. 3 is a left side elevational view thereof;

FIG. 4 is a bottom plan view thereof;

FIG. 5 is a rear elevational view thereof;

FIG. 6 is a top plan view thereof; and FIG. 7 is a sectional view taken along line 7—7 of FIG. 6.

The side opposite FIG. 3 is a mirror image of that shown in FIG. 3.

FIG. 1.

FIG. 2.

FIG. 4.

FIG. 3.

FIG. 5.

FIG. 6.

FIG. 7.
